(57) **CLAIM**

I claim the ornamental design for container with nail files, as shown and described.

DESCRIPTION

FIG. 1 is a perspective view of a container with nail files;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown represent portions of the container with nail files that form no part of the claimed design.

1 Claim, 5 Drawing Sheets
